DESIGN FOR AN INKWELL

Nathaniel A. Reinhart, San Francisco, Calif.

Application June 23, 1945, Serial No. 120,295

Term of patent 14 years

(Cl. D74—8)

To all whom it may concern:

Be it known that I, Nathaniel A. Reinhart, a citizen of the United States of America and a resident of the city and county of San Francisco, and State of California, have invented a new, original, and ornamental Design for an Inkwell, of which the following is a specification, reference being had to the accompanying drawing, forming part of this application, in which:

cap structure in extended position, showing my new design;

Figure 2, a side elevation of my inkwell with the cap structure in retracted position; and

I claim:

The ornamental design for an inkwell, substantially as shown.

NATHANIEL A. REINHART.
